FREDERICK S. MEYER, OF MINNEAPOLIS, MINNESOTA.

APPARATUS FOR FORMING MOLDS FOR INLAYS AND CROWNS.

Application filed July 2, 1927. Serial No. 203,237.

This invention relates to dental apparatus for casting inlays and crowns and especially to apparatus for preparing and forming the mold.

5 In carrying out the usual process for forming the casting mold for inlays or crowns the wax model is first carefully prepared and attached to the end of a sprue or pin. The sprue with the model thereon is next mounted in upstanding position upon a crucible former in axial alinement therewith and a so-called investment ring is connected with said crucible former surrounding the wax model, and forming in conjunction with said 10 crucible former an investment container. The container so formed is filled with the investment compound in plastic semi-liquid condition and the investment is permitted to set or harden with the wax model disposed 15 therein. The elimination of the wax model from the mold is then necessary to complete the preparation of the mold.

I have developed, through extensive experimental work, a technique for investing 25 the wax model which overcomes to a large extent, the distortion of the wax model and which further overcomes or compensates for shrinkage of the gold in the process of casting. A highly efficient apparatus is necessary to successfully carry out my technique and it is, therefore, the main object of this 30 invention to provide simple but highly efficient apparatus, including a crucible former, sprue and investment ring, the combination, co-operation and co-action thereof when used in connection with my technique producing a nearly perfect mold for the casting 35 of an inlay or crown.

The container formed by the usual investment ring and crucible former is filled with the investment compound in semi-fluid state, said compound being mixed with a substantial 40 amount of water. In the standard rings and crucible formers now in use the ring loosely surrounds a circular flange as described, and always small amounts of water escape from between the bottom of the ring and said crucible former. The slightest escape of water therefrom causes the investment compound 45 to settle towards the bottom, tending to cause a distortion of the wax model.

It is, therefore, a further object of my in-

vention to provide an investment ring and crucible former capable of water tight connection to form the investment container and further capable when so joined of being lifted or carried as one unit without displacement of the investment material when in fluid state and without distortion of the wax model disposed therein.

60 Sprues used heretofore have been objectionable in forming molds for the smaller inlays due to the fact that the model will usually be slightly distorted at the time the heated sprue is inserted therein, the slightest 65 tilting of the heated sprue relatively to the model causing the distortion. In casting inlays or crowns with a centrifugal casting machine a relatively larger sprue aperture is desirable in the mold to insure the proper passage of gold than when casting with the pressure casting machine. Consequently, a sprue 70 of substantial diameter must be used in preparing molds for the use in centrifugal machines and heretofore sprues of substantially 75 uniform diameter throughout have been utilized with imperfect results in the forming of the smaller castings.

It is, therefore, an additional object of my invention to provide in my apparatus a sprue 80 adjustable in diameter to meet the requirements for either a centrifugal or pressure type of casting machine and furthermore capable of effecting a relatively large sprue 85 aperture in the mold without occasioning the objectionable distortion above described.

A further object of my invention is to provide an investment ring adapted to be detachably connected to a crucible former with a water tight joint therebetween and further 90 having means adapted to retain the investment compound and lessen the tendency thereof to settle during the setting of said compound.

These and other objects of the invention 95 will be apparent from the following description made in connection with the accompanying drawings in which like reference characters refer to similar parts throughout the several views, and in which:

Fig. 1 is a side elevation of my apparatus assembled with the investment ring and mold shown in cross section;

Fig. 2 is a cross section showing the greater

part of my crucible former in plan and taken on the line 2—2 of Fig. 3;

Fig. 3 is an axial vertical section of my crucible former having a portion of the investment ring in connection therewith;

Fig. 4 is a side elevation of my crucible former having the wax model mounted thereon by means of my improved sprue;

Fig. 5 is a longitudinal section of one form 10 of my investment ring;

Fig. 6 is a cross section of my investment ring with the mold formed therein, taken on the line 6—6 of Fig. 1;

Fig. 7 is a longitudinal section of my preferred form of sprue detached; and

Fig. 8 is a longitudinal section of slightly different embodiment of investment ring than that shown in Fig. 5.

My improved crucible former comprises a 20 plug member or disc 7 having an axially disposed convex stud 7^a. A concentric groove 7^b surrounds stud 7^a, said groove being defined on its inner side by a tapered annular shoulder 7^c of considerable height. Groove 25 7^b is filled with some plastic sealing substance such as paraffin or beeswax, the purpose of which will later be explained.

A threaded socket is provided in crucible former 7 extending axially thereof and 30 through a considerable portion of stud 7^a and I provide a small sprue chuck 8 threadedly engaging said socket and having a longitudinally split inner end terminating in a conical extremity 8^a adapted to contact the truncated conical end of said socket, the longitudinal inward movement of chuck 8 within said socket causing the split inner end to be contracted to clamp the sprue therein.

My improved sprue comprises a plurality 40 of telescoped sections (preferably three) adapted to be adjustably slidable one within the other. As illustrated, an outer tubular section 9^a of approximately the diameter of relatively heavy sprues now in use is provided 45 having telescoped therein an intermediate tubular section 9^b, which telescopically carries the model pin 9. As shown, the several sections 9^a, 9^b and 9 are of equal length, and preferably are of substantially the height of 50 my crucible former from the base to the apex of the stud. Obviously, all of the sections may be projected above the apex of the stud 7^a of the crucible former, or if desired, the pin 9 may be alone projected to produce a 55 relatively small sprue hole in the mold, or if desired, either or both of the tubular sections may be projected for some distance above the apex of the stud 7^a and pin 9 projected a relatively short distance above the 60 upper end of said tubular members to engage the model. Pin 9 preferably has an engagement end of square cross section adapted to engage the model. The several sections of my sprue fit tightly and may be slidably adjusted and obviously may be employed in 65

connection with a crucible former whether or not the chuck 8 is used. If the chuck 8 is used the outer tubular section 9^a may be clamped in proper position therewith.

My investment ring preferably comprises 70 a cylindrical member 10 constructed of relatively thin material having a circumferential corrugation or bead 10^a disposed about its medial portion. I prefer to construct my ring in the manner shown in Fig. 8 with an 75 outwardly projecting corrugation, also numbered as 10^a, since there will be no tendency to in any way weaken the intermediate portion of the mold when that structure is used. Investment ring 10 is of the same diameter at 80 each end and either end may be snugly telescoped over the tapered annular shoulder 7^c of my crucible former, the peripheral edge of the engaging end being disposed within groove 7^b and its connection with crucible 85 former 7 sealed by means of the beeswax or other plastic material X disposed within said groove.

The letter Y indicates a wax model disposed on my sprue 9 having a relatively dense 90 inner investment Z thereon.

In preparing a mold for casting, the wax model is first obtained and placed upon the end of my sprue 9^a. Tubular sprue member 9^a is then mounted within the sprue chuck 8 being inserted from the upper stud end of the crucible former and is secured in proper position relative to stud 7^a. The desired section of the sprue is projected the proper distance from above the apex of stud 7^a, the square engagement end of pin 9 having been, of course, first heated and inserted into the wax model. If a relatively large sprue aperture connecting with the mold is desired; one of the larger sections of the sprue is projected from the apex of stud 7^a into close relation at its upper end with the wax model. My investment ring 10 is then telescoped at one end over shoulder 7^c, the edge thereof being tightly sealed by means of the tapered 110 shoulder and material X disposed within groove 7^b. I prefer to form a relatively dense inner investment Z about my wax model before filling the investment ring with investment material. My technique for the investment is of considerable importance but will not be described here as the process constitutes no part of this invention. The investment ring is next filled with a warm investment compound M and the crucible former and ring connected therewith are preferably disposed in an oven at the proper temperature to cause a certain expansion of the wax model to compensate for the shrinkage of the gold casting. After the investment is 115 set the crucible former 7 may, of course, be removed and with it the sprue and tubular member, said sprue leaving in said mold an aperture communicating with the wax model.

It will be seen that my investment ring 120

will be snugly connected with my crucible former, a water tight joint being interposed therebetween, due to the plastic material within groove 7^b and the tapered annular shoulder 7^c. The joined members constituting the investment container may be handled or moved as a unit without danger of displacing the parts, and there will be no leakage between the investment ring and crucible former and consequently no settling of the investment compound to distort the model.

The circumferential bead or corrugation in the medial portion of the investment ring 15 prevents displacement of the mold when heat is applied to the ring. Such displacement often occurred with rings heretofore utilized.

The functions and advantages of my improved sprue are probably clear from the foregoing description. My sprue may be utilized to form passages in the mold of three different diameters and further will prevent or minimize the distortion of the wax model when the pin is inserted, due to the fact that 25 engagement is made with the small pin 9, even when one of the larger tubular sections are used to form the sprue hole in the mold.

It is of great importance to adjust the sprue properly relative to the crucible former and to hold the same firm against displacement. This I may accomplish by the use of a simple but highly efficient chuck axially disposed with crucible former 7.

From the foregoing description it will be seen that I have invented, after extensive experimental work, highly efficient apparatus for forming molds for the casting of inlays and crowns, said apparatus being adapted to greatly lessen the damage of distortion of 35 the wax model.

It will, of course, be understood that various changes may be made in the form, details, arrangement and proportions of the parts without departing from the scope of 40 the invention.

What is claimed is:

1. Apparatus for forming a mold for inlays or crowns comprising an investment ring and a crucible former having an upstanding stud adapted to axially retain a sprue former, said crucible former having a tapered upstanding shoulder about which one end of said investment ring is adapted to snugly telescope to secure said parts together, said crucible former also having a groove encircling said shoulder in which one edge of said investment ring is adapted to be seated.

2. Apparatus for forming a mold for inlays or crowns comprising an investment ring 60 and a crucible former having an upstanding stud adapted to axially retain a sprue former, said crucible former having a groove surrounding said stud in which one end of said investment ring is adapted to be seated, and

a filling of plastic material in said groove 65 adapted to form a seal between said crucible former and said investment ring and adapted moreover to secure said parts together.

3. Apparatus for forming a mold for inlays or crowns comprising a crucible former 70 having a convex upstanding stud and means for connection with an investment ring, said stud being provided with a threaded axial socket extending from the base of said crucible former to a medial portion thereof and 75 terminating in a tapered seat, a chuck having engagement with said threaded socket and provided with a split inner end, and terminating in a tapered portion adapted to engage said tapered seat, and a sprue telescoped 80 within said chuck and projecting normally beyond the apex of said stud.

4. Apparatus for forming a mold for inlays or crowns comprising a crucible former adapted to be connected with an investment 85 ring and having an upstanding stud thereon, said stud having an axial port therethrough, and a sprue former comprising a tubular member telescoped within said port and a pin of smaller diameter telescoped within 90 said tubular member and longitudinally slidably therein.

5. In apparatus for forming a mold for inlays or crowns, a sprue adapted to be adjustably connected to a crucible former, comprising a plurality of telescoped sections, said inner section comprising a pin of relatively small diameter adapted to engage and retain the plastic model.

6. In apparatus for forming a mold for inlays or crowns, a crucible former comprising a body having a substantially annular shoulder about which an investment ring is adapted to be positioned, said body also having a groove encircling said shoulder in which one 100 edge of said investment ring is adapted to be seated and retained.

7. In apparatus for forming a mold for inlays, a crucible former comprising a body 110 adapted to carry a sprue former, said body having an annular groove in which one end of an investment ring is adapted to be seated and a filling of plastic material in said groove adapted to form a seal between said body and an investment ring and adapted moreover to 115 secure said parts together.

8. In apparatus for forming a mold for inlays or crowns, an investment ring adapted to be connected with a crucible former comprising a tubular body having an outwardly projecting circumferentially disposed bulge adapted to prevent displacement of a mold 120 therein, said bulge causing an enlarged portion to be formed in said mold between the ends thereof.

9. In apparatus of the class described, an investment ring having an annular edge at one end thereof and a closure for said end

having an annular groove therein in which the annular edge of said investment ring is adapted to be seated, and a filling of plastic material in said groove adapted to form a seal between said edge and said closure.

5 10. In apparatus of the class described, an investment ring having an annular edge at

one end thereof and a closure member for said end having a tapered annular shoulder about which said edge of said investment ring is adapted to snugly telescope to tightly secure said ring and closure together.

In testimony whereof I affix my signature.

FREDERICK S. MEYER.
